Filed June 22, 1971, Ser. No. 155,688

Term of patent 14 years

Int. Cl. D29—99

U.S. Cl. D72—1 R

FIG. 1

FIG 2

FIG 3

FIG. 1 is a perspective view of an indicator panel for a security alarm system portable test unit showing my new design;

FIG. 2 is an elevational view as taken from the left side of FIG. 1; and

FIG. 3 is an elevational view as taken from the bottom of FIG. 1.

The broken line showing of the housing is for illustrative purposes only and forms no part of the claimed design.

I claim:

The ornamental design for an indicator panel for a security alarm system portable test unit, substantially as shown and described.
